No. 657,598.

Patented Sept. 11, 1900.

L. HARRIS, Dec'd.
C. S. HARRIS, Executrix.
HOIST AND CARRIER.
(Application filed Aug. 8, 1898.)

(No Model.)

UNITED STATES PATENT OFFICE.

CYNTHIA S. HARRIS, OF ROME, NEW YORK, EXECUTRIX OF LEWIS HARRIS, DECEASED, ASSIGNOR, BY MESNE ASSIGNMENTS, TO CYNTHIA S. HARRIS.

HOIST AND CARRIER.

SPECIFICATION forming part of Letters Patent No. 657,598, dated September 11, 1900.

Application filed August 8, 1898. Serial No. 688,129. (No model.)

To all whom it may concern:

Be it known that LEWIS HARRIS, deceased, late a citizen of the United States of America, and a resident of Rome, Oneida county, New 5 York, did invent certain new and useful Improvements in Hoists and Carriers, of which the following is a specification.

The invention relates to a hoist and carrier; and it consists in the mechanism hereinafter 10 pointed out and claimed.

Figure 1 is a side view of the operating mechanism of the apparatus. Fig. 2 is a side view of the apparatus of Fig. 1 looking at the opposite side thereof. Fig. 3 is a top view of 15 the machine in position for operation, portions of the frame being shown in cross-section. Fig. 4 is an end view of the drum with the gears removed, showing a side view of the friction-band and the lever for operating the 20 same. Fig. 5 is a vertical central section of the gear-drum and a full view of the shaft and mechanism for clutching the drum, the friction-band being shown in cross-section on the drum. Fig. 6 is a side elevation of the 25 machine. Fig. 7 is an end view of the car, the rail or track being shown in cross-section. Fig. 8 is an end view taken from the left of Fig. 2, illustrating modifications of structure 30 from that illustrated in Fig. 2.

In the drawings the several reference-numerals refer to corresponding parts in the several views.

While the machine permits of several structural changes which may occur to one skilled 35 in the art of manufacture of such machines, yet the best form in which the invention has been practiced is in the details of construction hereinafter more fully pointed out and claimed.

A track 1 is provided suitably supported 40 in an elevated position. In this instance the track is composed of I-beam steel. On the lower flanges 2 2 wheels 3 3 are mounted on the car pivoted at 4 between walls 5 5 of the 45 car. In the lower outer angles of the walls of the car grooved pulleys 6 6 are mounted. On the cable 7, between pulleys 6 6, carrying-pulley 8 is mounted, provided with a lifting and carrying hook 9 for engaging and carrying 50 the load. The end 10 of the cable is secured to track 1 at the point to which the load

on the car is desired to be moved, and the cable passing over one of the grooved pulleys 6 receives carrying-pulley 8, passes over the other pulley 6 of the car, and is secured to 55 and wrapped on cable-drum 11, which has on one edge flange 12 and on the other end has a friction-band 13. Cable-drum 11 is mounted to run loosely on shaft 14, which passes through hub 15 of the said drum, the shaft 60 being mounted in suitable frame 16, secured to stationary supports. On the inside end of drum 11 a beveled edge 17 is provided, which fits over the beveled surface 18 of drum-head 19, which in this instance is made of wood to 65 increase the friction. The drum-head 19 is splined rigidly to the shaft 14 and fits into flange 20 of gear-wheel 21 and is rigidly secured thereto. The beveled overlapping rim of the cable-drum receives the beveled surface of 70 the head, the two when brought in contact forming a friction - surface to engage each other and forms the clutching mechanism for controlling the drum. The clutching and unclutching mechanism for bringing the surfaces into or out of friction engagement with 75 each other is operated by incline shoulder 22 on shaft 14 and loosely secured thereto. Rigidly secured to shaft 14 is a flange having on its side an incline shoulder 23, which is in 80 contact with shoulder 22. A lever 24, depending from the shoulder 22, operates the latter, so that the drum is moved into or out of contact with the friction-head, either securing the drum to the friction-head or with- 85 drawing it from contact therewith. When the cable-drum is loose from the friction-head, the load may be lowered through the operation of gravity. For regulating or controlling the motion of the drum band 13 is 90 provided, which is rigidly secured to the frame at 27 and partially surrounds the drum and is attached at 29 to shaft 30. Lever 28 is rigidly attached to shaft 30, so that by drawing down on cord 31 the speed of the 95 drum is controlled by the operator by friction engagement of the band with the drum, which is best illustrated in Fig. 4 of the drawings.

Power is imparted to the machine through fly-wheel 32, (best illustrated in Fig. 3,) which 100 fly-wheel is rigidly secured to shaft 33, which carries small driving-gear 34, splined to the

shaft 33 and meshing into the drum-gear 21. The gear 35 on the shaft 33 meshes into gear 36, splined to shaft 37, mounted on the frame 16. Through these gears a reversed motion is applied to shaft 37. For reversing the rotation of the parts shaft 38 is provided, mounted to rotate in brackets or standards 39 39, Figs. 2 and 3, pivoted to the frame 16 at 40, so that the shaft is free to rock on the pivotal points of the brackets 39 39. The shaft 38 carries friction-drum 41, which in this instance is wood, to increase the friction and may be brought alternately into contact with friction-drums 35^a on shaft 33 and 36^a on shaft 37 for reversing the rotation of the shaft 38, on which is splined grooved-face rope-pulley 42, which drives rope 43, which is attached at opposite sides of the car 44 at 45 45, the rope extending over idle pulley 46 and groove-pulley 42, to which it is held. The rock-shaft 38 is operated to throw the drum 41 into or out of engagement with friction-drums 35^a or 36^a through the medium of arm 47, mounted on shaft 38. Rigidly fixed or rigidly secured to arm 47 is lever 48. Friction-drum 41 is alternately brought into engagement with drum 35^a or 36^a, and by this mechanism an alternate reverse motion is imparted to shaft 38 and pulley 42 and to car 44 through the rope and the mechanism driven by the machinery already pointed out. If the operator desires to hoist the load into an elevated position, he moves the lever 24, thereby driving the drum onto the drum-head 35 into friction therewith and connecting mechanism which drives the drum, wraps the cable on the drum, and lifts the load. If the operator desires to lower the load, he operates lever 24 in a way to move the drum out of friction-contact with the head, and at the same time the load will drop by gravity. When the load is hoisted to the required height, the operator moves lever 24 to disconnect the drum from the gear and pulls on cord 31 and applies the pressure of the friction-band 13, and thus holds the load and drum. When the load is at the requisite height and it is desired to carry the same either to or from the machine, it is accomplished by operating lever 48 in the direction to which the load is desired to be transferred. By the movement of the lever either to the right or to the left the friction-drum 42 is thrown into contact either with drum 35^a and 55 out of contact with friction-drum 36^a, or it is thrown out of contact with friction-drum 35^a and into contact with friction-drum 36^a, which moves grooved drum 42 or reverses the same, so that the load can be driven out or drawn 60 in at the will of the operator.

In the mechanism illustrated in Fig. 8 the grooved-face pulley 42, which carries and drives rope 43 for operating the car in or out, is mounted on a journal supported on the frame at 40, Fig. 2, so that the center of the pivotal point of the swinging arms 39 and the center of the journal are the same, and

on this journal gear 42^a is mounted, which is rigidly secured to groove-pulley 42, both running together freely on the journal, which supports them. On the end of shaft 38, which carries the wood friction-pulley, which is mounted to be swung into contact with the two friction-rollers for reversing the movement of the parts, gear-wheel 42^b is mounted, 75 splined to the shaft. The gear 42^b meshes into gear 42^a and imparts to it and the groove-pulley an alternate rotary motion when the wood friction pulley or drum is swung into or out of contact with the two friction rollers 80 or drum for reversing the movement of the parts. By this arrangement the location of the groove-pulley 42 is sustained on the frame in a given space and is not moved with the friction-drum. By this arrangement the 85 same tension is always maintained on the rope or cable for moving the car.

It is obvious that instead of using the gear-wheels already described pulleys and belts may be substituted in their place and accomplish the same end. The gears, however, are preferred because of their positive engagement and freedom from slipping, which might occur if belts were used.

What is claimed as new, and desired to be 95 secured by Letters Patent, is—

1. In combination, a track, a carriage traveling thereon and provided with pulleys, an idler-pulley at one end of the track, a frame, an operating mechanism therein comprising 100 a drive-shaft, a drum-shaft, a hoisting-drum thereon, a hoisting-cable thereon and extending over the carriage-pulleys and secured at the opposite end of the track, a band-brake engaging said drum and secured at one end 105 to said frame, a brake-operating lever to which the opposite end of said band is secured, one end of said drum being internally beveled, a head on said shaft having the beveled end to enter said beveled end of the drum, a gear rigid with said head and geared with said drive-shaft, means to move said beveled ends of the head and drum to and from each other to throw the drum into and out of gear with the drive-shaft, another shaft provided with 110 a cable-driving pulley, the carriage-moving cable actuated by said pulley and passing around said idler and attached to said carriage, reversing driving mechanism between said drive-shaft and said cable-driving pulley comprising a swinging support having a hand-operating lever, substantially as described.

2. In combination, a frame, a rotary drive-shaft therein, a hoisting-drum shaft geared 125 to the drive-shaft, a hoisting-drum, a manually-operated clutch to throw the drum into and out of gear with said shaft, a pair of oppositely-rotating shafts geared to said drive-shaft and provided with adjacent separated 130 friction-disks, a driven shaft provided with a friction-disk arranged opposite, adjacent, and adapted to move into engagement with either of said first-mentioned disks, a mov-

able support for said driven shaft, means for moving the same, and a conveyer-cable pulley driven in either direction by said driven shaft, substantially as described.

5 3. In combination, in a hoisting and conveying apparatus, a track, a carriage movable thereon, a cable for moving the carriage back and forth on said track, a frame, a pulley-shaft, a pulley rigid on said shaft and receiving said cable to actuate the same in either direction, a drive-shaft, a counter-shaft driven from and in an opposite direction to the drive-shaft, friction-disks rigid with the drive and counter shafts, a friction-disk driving said pulley-shaft, a swinging support for said pulley provided with manually-operated moving means, and arranged to move said friction-disk into engagement with either of said disks rigid with said drive and counter shafts, substantially as described.

4. In a hoisting and conveying apparatus, the combination, of a track, a frame at one end thereof, an idler-pulley at the opposite end thereof, a carriage movable back and forth on said track and having pulleys mounted therein, a drive-shaft in said frame, a cable-hoisting drum therein, a clutch mechanism between said drum and said shaft, a hoisting-cable from said carriage to said drum, a shaft in said frame having a cable-pulley rigid thereon, a cable on said pulley and passing around said

idler and secured to said carriage to move the same back and forth on said track, and reversing driving gearing and shafting between said pulley-shaft and said driving-shaft provided with manually-operated movable controlling means, whereby said single pulley can be operated in opposite directions, substantially as described. 35

5. In a hoisting and conveying apparatus, the combination, of a frame, a drive-shaft therein, a counter-shaft geared to the drive-shaft, said shafts rotating in opposite directions and provided with adjacent friction-disks, swinging arms carried by the frame, 45 a pulley-shaft carried by said arms between the planes of the axes of said drive and counter shafts, said pulley-shaft having a friction-disk opposite and capable of engaging and being driven by either of said first-mentioned 50 disks, means to move the pulley-shaft to bring its disk into contact with either of said first-mentioned disks, and a cable-pulley rigid on said pulley-shaft, substantially as described.

Signed at Utica, New York, this 28th day of 55 July, 1898.
